UNITED STATES PATENT OFFICE.

MOSES C. JOHNSON, OF MILFORD, CONNECTICUT.

SHEARS.

SPECIFICATION forming part of Letters Patent No. 244,614, dated July 19, 1881.

Application filed October 9, 1880. (No model.)

To all whom it may concern:

Be it known that I, MOSES C. JOHNSON, of Milford, in the county of New Haven and State of Connecticut, have invented a certain 5 new and useful Improvement in Shears, of which the following is a description.

The object of my invention is to provide a very desirable and useful means of taking up the wear of shear-blades and keeping the cutting-edges as nearly coincident as possible.

To this end the invention consists in the combination, with two shear-blades and the pivot connecting them, one of said blades having in rear of said pivot a screw-threaded hole counterbored upon the inner side of the blade, 15 of a plug or saddle of metal in said counterbore, and a screw fitting said screw-threaded hole and serving to press the plug or saddle against the opposite blade, and thereby bring 20 the cutting-edges of the blade coincident.

In the accompanying drawings, Figure 1 represents a side view of a pair of shears embodying my invention. Fig. 2 represents an edge view thereof; and Fig. 3 represents a transverse section upon the dotted line xx , Fig. 1.

Similar letters of reference designate corresponding parts in all the figures.

Although I have only shown my invention as embodied in shears of a peculiar form, it is 30 applicable to shears of any other ordinary construction.

A designates the handles, which are pivoted together by a pin or pivot, a , and have arms A' projecting outward in opposite directions.

B designates the blades, which are pivoted together by a pin or pivot, b , and have arms

B' projecting outward in opposite directions. The arms A' of the handles A are connected with the arms B' of the blades B by pins or pivots c , thus forming a toggle arrangement of 40 levers which gives the shears great power.

The shears shown are particularly adapted for metal; and C designates a sheet of metal being cut.

I will now describe my improved means of 45 taking up wear.

In one blade, in rear of the pivot b , is formed a screw-threaded hole, d , in which is fitted a screw, D. The hole d is counterbored upon the inner side of the blade, and in said counterbore is fitted a plug or saddle, E, of any suitable material—such, for instance, as Babbitt metal—which, by turning said screw D inward, may be made to press upon the inner surface of the opposite blade, thus distributing 55 the pressure of the screw D upon a large surface and keeping the cutting-edges of the two blades coincident. When it is found that by reason of wear the shears are defective the defect may be remedied by simply setting up the 60 screw D.

What I claim as my invention, and desire to secure by Letters Patent, is—

The combination, with the blades B B and their pivot b , one of said blades having a screw-threaded hole, d , and a counterbore upon its inner side, of the tightening-screw D and the plug or saddle E, substantially as specified.

MOSES C. JOHNSON.
